WEFT-CHANGING MECHANISM FOR LOOMS

Harry Bracewell, Dadar, Bombay,
British IndiaApplication May 20, 1941, Serial No. 394,341
In British India January 8, 1941

20 Claims. (Cl. 139—243)

The invention relates to looms and has more particularly for its object to provide means for automatically replenishing the weft in a loom.

For convenience in terminology, throughout the present specification the term "pirn" means the bobbin with or without weft-thread wound thereon which, when in operative use during weaving, is accommodated in a shuttle. The term "shuttle" means the envelope or case in which the pirn is shuttled to and fro through the warp threads to effect weaving. A "full" shuttle is one in which the pirn contained therein is fully wound with weft-thread or has at least a certain amount of weft-thread remaining on the bobbin which is still usable in the weaving operation of the loom. A "spent" or exhausted shuttle is one in which the pirn is exhausted of weft-thread or of which the weft-thread has broken or requires changing, thereby exhausting the immediate use of the pirn in the weaving operation of the loom. The term "picker" means the mechanism provided for effecting the propulsion of a shuttle through the warp threads from one side of the loom to the other.

Hitherto, the automatic replenishing of the left-thread in a loom has usually been effected in either one of two alternative ways. According to one method, the loom operates with an automatic pirn-changing mechanism whereby a single shuttle is used and when the pirn is exhausted of weft-thread a fresh full pirn from a battery or magazine of pirns is introduced into the shuttle, such as by a hammer type of pirn-changer which forces a fresh pirn into the shuttle by a blow from the hammer, generally vertically, and simultaneously discharges the exhausted pirn from the shuttle. According to the other method, a battery or magazine of shuttles is provided; in or associated with a common shuttle-box, together with a shuttle-changing mechanism whereby as soon as the pirn in the operative shuttle is exhausted of weft-thread the shuttle with the exhausted pirn is discharged from the shuttle-box into another receptacle and a fresh shuttle with a full pirn is introduced into the shuttle-box in its place. The discharged shuttle is then taken away to be replenished by hand with a full pirn and is introduced again into the magazine of shuttles.

However, both methods have their disadvantages. In the pirn-changing type of automatic mechanism the one shuttle is in operation the whole time and thereby becomes heated, which is disadvantageous. Also, the time available for the

change of the pirn is extremely short as the exhausted pirn has to be discharged and a new pirn introduced into the shuttle during the return movement of the slay of the loom, which is generally a matter of a fraction of a second only. In the shuttle-changing type of automatic mechanism, on the other hand, the discharge of the shuttles from the shuttle-box frequently causes damage to them and furthermore a large supply of shuttles is required.

Also, it has only been found possible hitherto to apply the automatic pirn-change and shuttle-change mechanisms above described to "underpick" looms owing to the reservoir or magazine required for the pirns and/or shuttles and the transfer mechanism adopted not being compatible with the design and operation of the other parts of the operative mechanism of an "overpick" loom. This is a serious disadvantage which has hitherto prevented the adoption of automatic weft-replenishing means to any extent in the looms in use in certain countries where practically the whole of the weaving machinery is of the "overpick" type and practically the whole of the weaving labour is therefore accustomed to "overpick" looms.

The present invention has for one object to provide an improved weft-replenishing means for a loom which overcomes the stated disadvantages inherent in the automatic pirn-changing and automatic shuttle-changing mechanisms previously proposed.

It has for another object to provide an improved automatically operating weft-replenishing means for a loom which may be applied to an "overpick" loom or to an "underpick" loom, as desired, and which may particularly be designed for and used in an "overpick" loom, and more particularly as an attachment which may be added to an existing "overpick" loom without necessitating any substantial alterations in the latter.

It has for a further object to provide an improved automatically operating weft-replenishing means for a loom which allows a much longer time for the replenishment of the weft than the automatic means previously proposed and which gives a more gentle action and a better chance of a perfect replenishment and satisfactory continuance in the operation of the loom than with vertical replenishments as hitherto.

It has for a still further object to provide an improved automatically operating weft-replenishing means for a loom which may be used with

standard pickers and their associated mechanism and which is simple and economical in manufacture, installation, use and maintenance.

The improved weft-replenishing means in accordance with the invention is based on the fundamental conception of combining in the one mechanism the advantages of both the pirn-change and shuttle-change types of automatic weft-replenishing mechanisms previously proposed, whilst eliminating their disadvantages. Thus, in accordance with the invention, it is proposed to employ a number of shuttles so as to avoid the disadvantages of the single shuttle of the pirn-change mechanism previously proposed, but to use only a small number of such shuttles and to combine with them the pirn-change principle whereby the few shuttles may be replenished automatically when not in immediate use and be successively brought back again before the picker for use, thereby avoiding the necessity of a large supply of shuttles, their discharge from the shuttle-box under conditions wherein they may become damaged and their replenishment outside of the loom such as is required in the automatic shuttle-change mechanism previously proposed.

In a specific and preferred form of the invention for accomplishing the desired objects, and as applied particularly to an overpick loom of the known type having the shuttle-housing and picker mechanisms thereof carried on a swing rail and a weft-feeler means for indicating the failure of the weft-thread, there is provided the combination of a revolvable multiple-compartment shuttle-box carried on the swing rail of the loom, having at least three compartments and each of the compartments of which is adapted to house an individual shuttle, means controlled by the said weft-feeler means whereby upon the weft-thread failing the said multiple-compartment shuttle-box is caused to revolve a part of a turn at a succeeding "beating-up" movement of the slay of the loom to displace a shuttle-housing compartment thereof from opposite the picker of the loom and to bring the next succeeding shuttle-housing compartment thereof into the vacated position opposite the picker, a pirn-changing mechanism including a stationary pirn magazine mounted towards the front of the loom and a pirn-transfer member fulcrumed on the swing rail of the loom, the said pirn-changing mechanism being so positioned relatively to the said multiple-compartment shuttle-box that when the said box is revolved to displace a compartment thereof from opposite the picker yet another compartment thereof is brought into cooperative relationship with the said pirn-changing mechanism, and means controlled by the "beating-up" movement of the slay of the loom at the immediately next pick of the loom succeeding the change of shuttles from opposite the picker, whereby the said pirn-changing mechanism is caused to operate by a blow from the hammer to effect a substantially horizontal transfer with a fresh pirn from the magazine from the front of the loom in counter-stroke to the movement of the shuttle-box as it approaches with the slay from the back of the loom, whereby to refill with a fresh pirn the shuttle in that compartment of the said multiple-box which has been brought into cooperative relationship with the said pirn-changing mechanism.

The invention as to its basic features of novelty may, however, be considered from a number of different aspects, each of which may be con-

sidered as being of importance per se, and these will be more specifically explained in the following description and illustrated in the accompanying drawings and defined separately and in combination in the appended claims.

In the drawings:

Fig. 1 is a side view of part of a loom showing the loom slay carried on a swing rail together with an automatic weft-replenishing means according to the invention;

Fig. 2 is a front view of the mechanism illustrated in Fig. 1; and

Fig. 3 is an enlarged sectional view of the multiple-compartment shuttle-box and pirn magazine of the invention taken along the line III-III of Fig. 2.

Fig. 4 is a time-action chart illustrating the cycle of operations of the mechanism.

Fig. 5 is a detail horizontal sectional view through the loom illustrating parts of the shuttle replenishing mechanism.

Fig. 6 is a detail section on the line 6-6 of Fig. 5.

The invention is illustrated in the drawings as applied to an overpick loom of the known type having the shuttle-housing and picker mechanisms and the slay of the loom carried on a swing rail and only those parts of the loom necessary to the understanding of the invention are illustrated and will hereinafter be referred to.

As illustrated, the slay 1 is carried in known manner by the slay sword 1a on the swing rail (or rockshaft) 2 of the loom. The loom being of the overpick type, the picker P is adapted to be whipped along the picker spindle or rail s (which extends over the top of the shuttle-housing mechanism) by the picker staff T. All these parts are of known standard construction.

In accordance with the invention, mounted on stub-shafts 4 in a frame-work 3 secured at one side to the said slay-sword 1a and fulcrumed at the other side on the swing rail 2, is a revolvable multiple-compartment shuttle-box 5. The construction of this shuttle-box is shown more particularly in Figs. 2 and 3 from which it will be seen that it is of generally cylindrical form and is revolvable about its longitudinal axis on the stub-shafts 4. It comprises a central axis-part 6 from which radiate (as shown) four brackets 7 each of which carries an individual open-topped and open-backed compartment or box 8 adapted to house a shuttle S. Each of the said compartments or boxes is open-topped because when in the top position of the box opposite the picker it must allow for the passage of the picker P as it is being whipped along the rail s. The said multiple-compartment shuttle-box is revolvable on its stub-shafts 4 in the frame-work 3, in order to bring each of its four compartments in turn into the top position opposite the picker P, by means of a chain-wheel 9 mounted on one of the said stub-shafts and which is connected by means of a chain 10 to a driving chain-wheel 11 which is rotatably mounted on a stub-shaft 12 carried by the lower end of the slay-sword 1a. The chain-wheels 11 and 9 are preferably in a two to one ratio whereby rotation of the driving chain-wheel 11 by one-eighth of a turn rotates the wheel 9, and thereby the revolvable shuttle-box 5, by one-quarter of a turn, i. e. the distance between two consecutive compartments or boxes thereof.

The wheel 11 has formed integrally therewith, or keyed thereto, to one side of the wheel proper, a wheel-shaped driving part including

driving bars 11a (shown more particularly in Fig. 2) by means of which the rotation of the wheel 11 is effected under the co-operative control of a lug or projection 13 pivoted at 14 in a bracket 15 bolted to the stationary frame-work 16 of the loom and which may be lowered into and raised out of operating position relatively to the said driving chain-wheel 11 by means of a control-rod 17. To this end, the lower end of the said control-rod 17 is pivotally connected to the lug 13 and the upper end thereof is connected by a link 18 to a horizontal rod 19 connected to the weft-fork of the loom (not shown) and which thereby forms part of the weft-feeler motion. The weft-feeler motion is at the opposite side of the loom from the weft-replenishing motion but as it may be of any of the many types of weft-feeler motions and is not a part of the invention, it is not illustrated or described in detail. The arrangement of the described mechanism is such that when the weft-thread fails the weft-fork remains down and causes rotation of the horizontal rod 19 which in turn depresses through the link 18 the control-rod 17 and lowers the lug 13 into its operating position relatively to the chain-wheel 11. The latter is caused to revolve, and with it the multiple-compartment shuttle-box 5, when the driving bars 11a thereof are brought into engagement with the said lowered lug 13 when the slay and slay-sword carrying the said wheel next approach the said lug during a forward or beating-up movement of the slay. The weft-fork and connected control-rod 17 may be returned into, or assisted in their return into, their normal positions by means of a spring (not shown).

In order to maintain the multiple-compartment shuttle-box 5 steady when not being revolved, a hammer 32 controlled by a spring 33 bears against a squared wheel 34 fixed to one of the said stub shafts 4 of the box.

For co-operation in the control of the pirn-change operation for a shuttle which is not opposite the picker of the loom, the control-rod 17 has also fixed thereto, such as by a set-screw, an arm 20 the extremity of which, when the control-rod 17 is depressed, is adapted to come below the lip 21a of a lever 21 which is fixed to the top end of another lever 22 which is pivotally mounted at its centre 23 in a slotted bracket 23a carried by the framework 16 of the loom.

The top face of the lip 21a is beveled and the lower face of the extremity 20a of the arm 20 is also preferably beveled and the arm 20 is resilient so as to yield in a horizontal direction. In the normal position of the rod 17 the extremity 20a of the arm 20 is disposed above the lip 21a and upon depression of said rod the engagement of the beveled surfaces causes lateral deflection of the resilient arm 20 whereby the extremity 20a assumes a position below the lip 21a as shown in the drawings. When the rod 17 is lifted, however, the extremity 20a engages the lip 21a and lifts the lever 21 for a purpose to be hereinafter more fully described.

A pirn-changing mechanism comprising a pirn-magazine 24, shown in Figs. 1 and 3 but not in Fig. 2, is stationarily mounted on the framework 16 towards the front of the loom in such a position that the discharge-end 25 of the said magazine through which a pirn is to be discharged is located in exactly the right position

for the transfer of a pirn into a compartment of the multiple-compartment shuttle-box 5 when the slay-sword 1a carrying the said box is in the forward or beating-up-position. The pirn-changing mechanism is of the hammer-type, the pirn transfer member comprising a hammer-head 26 mounted on a hammer-lever 27 which is hinged at its centre 28 and is fulcrumed at its lower end 29 on the swing rail 2 of the loom. The said hammer-lever 27 is held straight by a spiral spring 30 which nevertheless yields in order to prevent breakage of machine parts should any obstruction interfere with the proper transfer of a pirn from the magazine 24. The hammer-lever 27 is normally held in its forward position by the tension of a spring 27a. The said pirn-transfer mechanism is adapted to be operated under the joint control of an operating stud or projection 31 carried on the lower end of the lever 22 and of a stud 35 fixed to the slay-sword 1a. This stud 35 is adapted to co-operate with the end of the lever 21, when the latter has been raised into the operative position by the cooperation of the raised extremity 20a with the lip 21a, in such a manner that when the slay-sword 1a is moving into the forward or beating up position it pushes back through the stud 35 the said lever 21 and thereby causes the lever 22 to pivot around its fulcrum 23, whereby the stud or projection 31 is caused to engage behind the pirn-transfer hammer 27 and to displace it in the opposite direction to the movement of the slay-sword 1a, in order to strike a pirn out of the magazine 24 into that compartment of the multiple shuttle-box 5 which is in a position ready to receive it.

Fig. 4 is a time-action chart showing in a general way the sequence of events in the operation of the weft-changing mechanism. The diagram represents two picks because the cycle of operations extends over a period of that duration. The points on the circle designated F. C. correspond with the front center position of the loom crank and the points B. C. correspond with the back center position. At the point I the loom crank is at the front center and the operative shuttle is at the starting side of the loom. From points I to II, when the weft in the operative shuttle is exhausted, the weft-work motion causes the horizontal shaft 19 to rotate and thus the link 18 depresses the control rod 17 and also the lug 13. From II to III the operative shuttle is traveling to the battery side of the loom. At the point represented at III the operative shuttle is in the multiple shuttle box. From III to IV the slay comes forward and the lug 13 engages with one of the driving bars 11a of the chain wheel 11 thus causing said wheel to rotate and, through the chain 10, the multiple shuttle box is turned a quarter of a revolution thereby taking the exhausted shuttle out of operation, and disposing the compartment of the shuttle box containing a fresh pirn in operative position. At the point IV the loom crank is at the front center with the operative shuttle in the shuttle box. From IV to V the control rod 17 is lifted to its original position by a spring and thus the lug 13 is lifted out of the path of the bars 11a. The arm 20 fixed to the rod 17 participates in this upward movement and raises the lever 21 into horizontal position. From V to VI the full shuttle is traveling to the starting side of the loom. From VI to I the slay sword

comes forward and the stud 35 comes into contact with the lever 21 and pushes it toward the front of the loom, thus causing the transfer hammer head 26 to press a full pirl into the front shuttle compartment. When the lever 21 is pushed to the front of the loom it falls off of the arm 20 and remains down and is therefore out of the path of the stud 35 until the next change takes place.

The complete automatic operation of the described mechanism is as follows:

On the weft-thread failing, such as due to the pirl in the operative shuttle being exhausted or breaking, the weft-fork operates in known manner on the backward beat of the slay when the shuttle is moving towards the multiple shuttle-box side of the loom and causes the horizontal rod 19 to rotate, which in turn depresses through the link 18 the control-rod 17. This lowers the lug 13 into operative relationship with the chainwheel 11, 11a and at the same time lowers the extremity of the arm 20 below the lip of the lever 21, the beveled surface of the lip 21a and extremity 20a deflecting the resilient arm 20 during this motion. These operations take place during the time that the spent shuttle returns into its compartment of the multiple shuttle-box 5. At the same pick of the loom, when the slay-sword and slay on the swing-rail 2 are moving into the forward or beating-up position from the back centre to the front of the loom in the direction of the straight arrow A shown in Fig. 1, one of the driving bars 11a of the chain-wheel 11 are brought into engagement against the end of the lug 13 and thereby cause the wheel to revolve one-eighth of a turn. This correspondingly revolves the multiple-compartment shuttle-box 5 by one quarter of a turn in the direction of the curved arrow B. This displaces that compartment of the said shuttle-box which houses the "spent" shuttle away from its top position opposite the picker of the loom and simultaneously brings into the vacated position that compartment of the shuttle-box which was turned towards the front of the loom opposite the pirl magazine 24 and which previously had been filled with a fresh pirl. Simultaneously, that compartment of the said shuttle-box which was in the position immediately preceding the said front position of co-operation with the pirl-changing mechanism is brought into the said front position. Therefore, upon the return of the spent shuttle into its compartment of the multiple-box after the weft-thread has failed, at the next pick of the loom a fresh shuttle with a full pirl is substituted for the "spent" shuttle and a shuttle to be replenished is presented to the pirl-changing mechanism.

During this pick of the loom at which the multiple-compartment shuttle-box 5 is revolved, as at all other picks of the loom during normal weaving when no shuttle or pirl-change at all are to be effected, the pirl-transfer mechanism 26, 27, does not operate because the extremity of the lever 21 has not been raised into operative relationship with the stud 35 on the slay-sword 1a in order to be operated thereby when the slay returns into its forward or beating-up position. There is, however, effected a preliminary or initiating operation for the pirl-change, which takes place by the extremity of the arm 20 on the depressed control-rod 17 being brought below the lip of the lever 21 which controls the

pirn-transfer. The latter operation is possible, however, only after the control-rod 17 has risen again with the weft-work when the said fork returns into its weaving position, because, through cooperation of the lip 21a and the extremity 20a, it thereby raises the end of the said lever 21 into position for co-operation with the stud 35 on the slay-sword 1a at the next forward or beating up movement of the slay. A small spiral spring (not shown), which may be fitted in any suitable position, may assist in raising the control-rod 17 and the weft-fork to the weaving position at the first pick with the fresh shuttle. During normal weaving no such raising of the end of the lever 21 into the cooperative position with the stud 35 on the slay-sword can take place because the control-rod 17 with the arm 20 has not been depressed, so that the said arm cannot rise again under the lip of the lever 21. This can only take place after the control-rod 17 has first been depressed by the failure of the weft-thread.

The next pick of the loom is effected with the fresh shuttle which has been moved in its compartment of the multiple-box 5 into the top operative position opposite the picker in the manner described. When the slay returns into its forward or beating-up position at this pick, the stud 35 carried thereby engages the end of the lever 21 and by pushing back the latter and thereby causing the lever 22 to pivot around its fulcrum 23, causes the stud or projection 31 on the lower end of the lever 22 to engage behind the pirl-transfer hammer lever 27 and to displace it in the direction towards the back of the loom to strike a pirl out of the magazine 24 into that compartment of the multiple shuttle-box which has been brought into the front position opposite thereto at the previous pick of the loom. It will be noted that in this transfer, as the multiple-compartment shuttle-box 5 is being carried in the forward or beating-up movement of the slay of the loom, the shuttle in the compartment thereof which is to be replenished is moving towards the pirl-magazine at the front of the loom and at the same time the pirl-change hammer head 26 on the hammer 27 is striking in the opposite direction to displace the fresh pirl from the magazine, thereby simultaneously giving it a movement in a direction towards the shuttle to be replenished. Both these movements take place on the same arc of a circle, since both the co-operating parts described are fulcrumed on the swing-rail 2 of the loom, and the transfer is effected substantially horizontally from the front of the loom. This facilitates the transfer, ensures a more gentle action than with vertical transfers and minimises possibility of faulty transfer.

The fresh pirl is struck by the pirl-transfer hammer 26, 27 in the manner described out of the pirl-magazine 24 into the shuttle 8 to be replenished and this simultaneously discharges the spent-pirl out of the shuttle. The spent-pirl is discharged through the open back wall of the compartment of the multiple shuttle-box and down in the direction of the curved arrow C shown in Figure 3 through a recess between the said compartment of the shuttle-box and the immediately succeeding compartment into a pirl-receiving receptacle (not shown).

In this and at subsequent picks of the loom, the multiple-compartment shuttle-box 5 is held steady by the action of the spring hammer 32, 33

which bears against the squared-wheel 34 fixed to the stub-shaft 4 of the shuttle-box.

As the lever 22 is swung to operate the hammer-lever 27 by the forwardly moving stud 35 the lip 21a slides across and disengages the extremity 20a and thus, as the hammer-lever is restored to normal position by the spring 21a during the succeeding rearward motion of the slay, the lever 22 is also returned to its normal position with the lip 21a lying directly below the beveled extremity 20a and out of the path of the stud 35.

In order to avoid the trouble known as "rebounding" shuttle such as frequently occurs in the previously proposed automatic weft-replenishing means, and which would foul the replenishment of the shuttle with a new pirn owing to the shuttle not being correctly positioned in its compartment of the multiple-box 5 for the pirn to be introduced thereto, means are provided for centralising a shuttle in its compartment of the multiple-box 5 during its displacement from opposite the picker (when spent) into the front position opposite the pirn-changing mechanism 24 for the replenishment of the weft. This shuttle-centralising means consists of two guide plates 36, 36a secured respectively to the framework housing the multiple-compartment shuttle-box, one on either side of the said box, and which extend respectively one towards the front and the other towards the rear so that in the successive positions taken up by the revolvable shuttle-box during its rotation, the shuttles in all the compartments thereof, whether they have overrun themselves or rebounded, are urged by the said guide plates from either side of the said box into the central position ready to receive a pirn from the pirn-magazine when brought in turn into the front position of the box in co-operative relationship with the said magazine.

It will be appreciated that the described construction and mode of operation of the automatic weft-replenishing means in accordance with the invention have numerous important and desirable features of general novelty. Thus, in view of the arrangement of the multiple-compartment shuttle-box 5 and its mode of operation, there results that each of the shuttle-boxes formed by the several compartments housing their individual shuttles is brought in turn into and displaced from a predetermined position which is the top position of operation in front of the picker. Furthermore, all the said shuttle-boxes with their shuttles are displaced simultaneously so that each shuttle-box is brought into the place vacated by another shuttle-box, one shuttle-box being displaced from opposite the picker, another one being simultaneously brought into the vacated place and a third one being presented to the pirn-changing mechanism. Furthermore, this is effected only upon the weft-thread failing and under the direct control of the weft-fork of the loom, due to the connection therefrom through the horizontal rod 19, link 18, control-rod 17 and lug 13 which operates the chain-wheel 11 at a succeeding beating-up or forward movement of the slay of the loom. Still further, by being revolvable on its stub-shafts 4, the multiple-compartment shuttle-box 5 operates in the described manner with a single direction of movement and the shuttles thereof are brought in turn to the picker of the loom to be picked and are then displaced from such position when spent, are replenished with weft

and are brought back again to the picker, all in the same direction of movement.

The pirn-change being effected by co-operation between the lever 21 and the stud 35 on the slay-sword, this makes it dependent upon the previous rotation of the multiple-compartment shuttle-box 5 to displace a spent-shuttle therefrom from opposite the picker, to bring a fresh shuttle into the vacated place and to bring a spent-shuttle opposite the pirn-changing mechanism, owing to the fact that the lever 21 can only be raised into the operative position if the control rod 17 has previously been depressed to revolve the multiple-compartment shuttle-box 5 and has been raised again carrying with it the arm 20. It furthermore ensures that the pirn-change is only effected at the next pick of the loom succeeding the change of shuttles opposite the picker and after the presentation of the spent shuttle to be replenished to the pirn transfer mechanism 24, 26, 27. It furthermore ensures that the pirn-change itself is effected in two stages at successive picks of the loom, the shuttle to be replenished being presented to the transfer mechanism at one pick and the actual transfer being effected at the next pick. Still further, the replenished shuttle is only presented again to the picker for further picking at a still later stage in the weaving when the shuttle is in operative use during the transfer has been spent.

These features of novelty in the construction and operation of the weft-replenishing means in accordance with the invention have a number of important practical advantages as compared to prior proposals of automatic weft-replenishing means. These are as follows:

Firstly, by the use of the multiple-compartment shuttle-box 5, each with its individual shuttle S, in combination with the automatic pirn-transfer mechanism for replenishing a shuttle while in its box when not opposite the picker, there is avoided the disadvantages of a single shuttle getting hot owing to continuous use thereof or of a large number of shuttles having successively to be used and discharged from a single shuttle-box, thereby causing damage to the same, because the shuttles never leave their respective boxes for replenishment.

Secondly, owing to a shuttle with its full pirn in its compartment of the multiple-compartment shuttle-box being all ready to be changed merely by revolving the shuttle-box a part of a turn upon the weft-thread failing, this ensures a substantially continuous operation of the loom without making the same dependent upon an immediate replenishment of a shuttle with weft which must be used immediately.

Thirdly, owing to the replenishment with weft being effected in two stages which take place at different picks of the loom, this results in the weft replenishment being effected over a much longer period of time than hitherto, thereby facilitating the transfer, promoting a certain and accurate transfer, minimising possible obtrusional difficulties and entailing a slower speed in the transfer with consequent less wear and tear and less possibility of defective operation of the machine parts.

Fourthly, owing to the spent-shuttle and fresh pirn to be introduced thereto being moved simultaneously towards one another on the same arc of a circle during the transfer, this further ensures a more gentle and accurate replenishment with weft than with vertical transfers.

Fifthly, owing to the constructional details of

the mechanism whereby a spent-shuttle to be replenished is displaced in its shuttle-box from opposite the picker of the loom and is brought into another position opposite a pirn-changing mechanism which is placed to one side of the operational mechanism of the loom proper i. e. to one side of the shuttle-housing and picker mechanisms and of the slay of the loom, this results in the mechanism being applicable either to underpick or overpick looms and, in the form described, being particularly adapted for attachment to an existing overpick loom of the known type having the shuttle-housing and picker mechanisms and the slay mounted for pivotal movement on a swing rail of the loom.

It will also be understood that the invention is not restricted to the specific details thereof which have been described above by way of example only and that many modifications of the embodiment described may be made within the scope of the appended claims. For example, it is not necessary that there should be only three or four shuttles each in its individual box or compartment of a multiple-box. There may be more, such as five or six. Also, although it is preferred that the shuttle-housing mechanism should be in the form of a multiple-compartment shuttle-box, it is not necessary that it should be of the revolving type specifically described. Still further, it is not necessary that the pirn transfer should be effected on that shuttle which is the immediately next one to be used in the weaving. By a suitable design of the various parts of the machine, it could be effected upon a spent-shuttle at any intermediate position between that when it is opposite the picker and that when it is to be presented again for use.

I claim:

1. In a loom having a picker-mechanism for picking the weft in a shuttle, the combination of a plurality of movable shuttle-boxes, each for housing an individual shuttle, means whereby each of the said shuttle-boxes may be brought in turn opposite the said picker for picking the shuttle thereof and may be displaced from such position when the shuttle is spent, means whereby a shuttle in its box which has been so displaced from opposite the picker may be presented to a pirn-changing mechanism, a pirn-changing mechanism for effecting the replenishment of such a shuttle with a fresh pirn, and means whereby the said pirn-changing mechanism only operates to effect such replenishment of the pirn at a pick of the loom subsequent to that at which the said shuttle was presented to the said mechanism.

2. In a loom having a slay and a picker-mechanism for picking the weft in a shuttle, the combination of a plurality of movable shuttle-boxes, each for housing an individual shuttle, means whereby each of said shuttle-boxes may be brought in turn opposite the said picker for picking the shuttle thereof and may be displaced from such position when the shuttle is spent, a pirn-changing mechanism so positioned relatively to the said shuttle-boxes that a spent shuttle in a shuttle-box which is not opposite the said picker may be replenished with a fresh pirn without leaving its box, means whereby the initiation of the said pirn-change is made dependent upon the displacement of a said shuttle-box from opposite the said picker, and means dependent for its operation upon the movement of the slay of

the loom for thereafter positively effecting the said pirn-change.

3. In a loom having a picker-mechanism for picking the weft in a shuttle and a weft-feeler motion for indicating the failure of the weft-thread, the combination of a revolvable multiple-compartment shuttle-box, each of the compartments of which constitutes a shuttle-box for housing an individual shuttle, and means whereby each of the said shuttle-housing compartments of the multiple-box may be brought in turn opposite the said picker for picking the shuttle thereof, and then be displaced therefrom when the shuttle is spent, such means including a driving wheel adapted to effect a part rotation of the said multiple-compartment box, a lug adapted to co-operate in effecting a part rotation of the said wheel and which is normally in a non-operative position relative to the said wheel, and means operative under the control of the said weft-feeler motion for displacing the said lug into an operative position relatively to the said wheel when the weft-thread fails.

4. In a loom having a slay, a picker-mechanism for picking the weft in a shuttle and a weft-feeler motion for indicating the failure of the weft-thread, the combination claimed in claim 3 including a driving wheel for effecting the rotation of the said multiple-compartment shuttle-box which is mounted to partake of the movement of the slay of the loom, a control rod, link-mechanism connected thereto and to the weft-feeler motion for depressing the said rod when the weft-thread fails, and a lug carried by the said control rod and which is adapted to be lowered thereby from a non-operative position into an operative position relatively to the said driving wheel in order to rotate the same when the said driving wheel is brought into engagement therewith at the next movement of the slay of the loom in the direction of the said lug.

5. In a weft-replenishing mechanism for a loom of the kind in which a spent shuttle is presented to a pirn-changing mechanism for receiving a fresh pirn, means whereby as the said fresh pirn is being introduced into the shuttle to be replenished the said shuttle and the fresh pirn are caused to move simultaneously towards one another.

6. In a loom having the shuttle-housing and picker-mechanisms thereof and the slay of the loom carried on a swing rail, the combination of a revolvable multiple-compartment shuttle-box also carried on the said swing rail and having at least three compartments, each of which constitutes a shuttle-box for housing an individual shuttle, means whereby the said multiple-box may be revolved to bring each of the shuttle-housing compartments thereof in turn opposite the said picker for picking the shuttle thereof and in turn in front of a pirn-changing mechanism to replenish the spent shuttle with a fresh pirn, and a pirn-changing mechanism including a stationary pirn magazine mounted towards the front of the loom and a pirn-transfer member fulcrumed on the swing rail of the loom, the arrangement being such that the replenishment of a spent shuttle when so presented to the pirn-changing mechanism is accomplished during a beating-up movement of the said slay and of the said multiple-box around the said swing rail and by a counter movement of the said pirn-transfer member also around the said swing rail, whereby both the fresh pirn and the spent shuttle are caused to move simultaneously towards

one another on the same arc of a circle during the purn transfer.

7. In a loom having the slay and the shuttle-housing and picker mechanisms thereof carried on a swing rail and a weft-feeler motion for indicating the failure of the weft-thread, the combination of a revolvable multiple-compartment shuttle-box also carried on the said swing rail and having at least three compartments, each of which is adapted to house an individual shuttle, means controlled by the said weft-feeler motion whereby upon the weft-thread failing the said multiple-compartment shuttle-box is caused to revolve a part of a turn at a succeeding "beating-up" movement of the slay of the loom to displace a shuttle-housing compartment thereof from opposite the said picker and to bring the next succeeding shuttle-housing compartment thereof into the vacated position, and a purn-changing mechanism including a stationary purn magazine mounted towards the front of the loom and a purn-transfer member fulcrumed on the said swing rail of the loom, the said purn-changing mechanism being so positioned relatively to the said multiple-compartment shuttle-box that when the said box is revolved to displace a compartment thereof from opposite the said picker yet another compartment of the said multiple-box is brought into co-operative relationship with the said purn-changing mechanism, and means controlled by the "beating-up" movement of the slay of the loom at the immediately next pick of the loom succeeding the said change of shuttle from opposite the picker, whereby the said purn-changing mechanism is caused to operate to refill with a fresh purn the shuttle in that compartment of the said multiple-box which has been brought into co-operative relationship with the said purn-changing mechanism.

8. In a loom having a slay and a picker mechanism for picking the weft in a shuttle, the combination of a plurality of movable shuttle-boxes, each for housing an individual shuttle, means whereby each of the said shuttle-boxes may be brought in turn opposite the said picker for picking the shuttle thereof and may be displaced from such position when the shuttle is spent, a purn-changing mechanism including a purn magazine and a purn-transfer hammer so positioned relatively to said shuttle-boxes that a spent shuttle in a shuttle-box which is not opposite the picker may be replenished with a fresh purn without leaving its box, a pivoted lever, a stud on said pivoted lever for controlling the operation of the said purn-transfer hammer, an operating lever on said pivoted lever adapted to be moved from a non-operative position into an operative position when the purn-transfer is to be effected, and a stud mounted to partake of the movement of the slay of the loom and which is adapted to push back the said operating lever as the slay moves in one direction of movement when the said lever has been moved into the operative position, whereby the said pivoted lever is caused to pivot and to engage the said stud carried thereby behind the purn-transfer hammer and to displace the same in the opposite direction to such lever-operating direction of movement of the loom slay in order to strike a purn out of the said purn magazine.

9. In a loom having a slay, a picker-mechanism for picking the weft in a shuttle and a weft-feeler motion for indicating the failure of the weft-thread, the combination of a revolvable multiple-compartment shuttle-box movable with

the said slay and each of the compartments of which constitutes a shuttle-box for housing an individual shuttle, and means whereby each of the said shuttle-housing compartments of the multiple-box may be brought in turn opposite the said picker for picking the shuttle thereof, such means including a driving wheel for affecting the rotation of the said multiple-compartment shuttle-box which is mounted to partake of the movement of the slay of the loom, a control rod, link-mechanism connected thereto and to the said weft-feeler motion for depressing the said rod when the weft-thread fails, a lug carried by and towards one end of the said control rod which is adapted to be lowered thereby from a non-operative position into an operative position relatively to the said driving wheel in order to rotate the same when the said driving wheel is brought into engagement therewith at the next beating-up movement of the loom slay subsequent to the failure of the weft-thread, a purn-changing mechanism including a purn magazine stationarily mounted towards the front of the loom and a purn-transfer hammer, a pivoted lever, a stud on one end of said pivoted lever for controlling the operation of the said purn-transfer hammer, an operating lever on the other end of the said pivoted lever which is normally in a non-operative position, an arm on the said control rod controlling the rotation of the said driving wheel which arm, when the said control rod is depressed upon the weft-thread failing, is adapted to be lowered below the said operating lever of the purn-transfer hammer to raise the said lever into the operative position, and a stud mounted to partake of the movement of the loom slay and which is adapted to push back the said operating lever when the latter has been raised into the operative position at the immediately next beating-up movement of the loom slay, whereby the said pivoted lever is caused to pivot and to engage the said stud carried thereby behind the purn-transfer hammer to displace the same in the opposite direction to the beating-up movement of the loom slay in order to strike a purn out of the said purn magazine.

10. In an overpick loom having the shuttle-housing and picker-mechanisms thereof and the slay of the loom carried on a swing rail and a weft-feeler motion for indicating the failure of the weft-thread, the combination of a revolvable multiple-compartment shuttle-box also carried on the said swing rail and having at least three compartments, each of which constitutes a shuttle-box for housing an individual shuttle, means whereby the said multiple-box may be revolved to displace a shuttle-housing compartment thereof from opposite the said picker and simultaneously to bring another one into its vacated place and to present a third one to a purn-changing mechanism, said shuttle-box-revolving-means including a driving wheel also mounted on the said swing rail, a control rod, link-mechanism connected thereto and to the said weft-feeler motion for depressing the said rod when the weft-thread fails, a lug carried by and towards one end of the said control rod which is adapted to be lowered thereby from a non-operative position into an operative position relatively to the said driving wheel in order to rotate the same when the said driving wheel is brought into engagement therewith at the next beating-up movement of the loom slay, a purn-changing mechanism including a purn magazine station-

arily mounted towards the front of the loom and a purn-transfer hammer fulcrumed on the swing rail of the loom, a pivoted lever, a stud on one end of said pivoted lever for controlling the operation of the said purn-transfer hammer, an operating lever on the other end of the said pivoted lever and which is normally in a non-operative position, an arm on the said control rod controlling the rotation of the said driving wheel which arm, when the said control rod is depressed upon the weft-thread failing, is adapted to be lowered below the said operating lever of the purn-transfer hammer to raise the said lever into the operative position, and a stud mounted to partake of the movement of the loom slay and which is adapted to push back the said operating lever when the latter has been raised into the operative position at the immediately next beating-up movement of the loom slay, whereby the said pivoted lever is caused to pivot and to engage the said stud carried thereby behind the purn-transfer hammer to pivot the same in the opposite direction to the beating-up movement of the loom slay in order to strike a purn out of the said purn magazine, whereby the said purn is struck into the spent shuttle which has been presented to the purn-changing mechanism while both the said fresh purn and the spent shuttle are moving simultaneously towards one another on the same arc of a circle.

11. In a loom having the shuttle-housing and picker mechanisms thereof and the slay of the loom carried on a swing rail, the combination of a revolvable multiple-compartment shuttle-box, each of the compartments of which constitutes a shuttle-box for housing an individual shuttle, means whereby the multiple-box may be revolved to bring each of the shuttle-housing compartments thereof opposite the picker for picking the shuttle thereof and be displaced therefrom when the shuttle is spent, and for a spent shuttle in a compartment of the multiple-box which is not opposite the picker to be presented to a purn-changing mechanism, a purn-changing mechanism including a stationary purn-magazine mounted towards the front of the loom, a purn-transfer member, and means operable during a beating-up movement of the slay towards the front of the loom whereby the said purn-transfer member is only caused to operate, to effect the transfer of a purn from the said magazine into the spent shuttle of that compartment of the multiple-box which has been brought into cooperative relationship with the said purn-changing mechanism, at a pick of the loom subsequent to that at which the said spent shuttle was presented to the purn-changing mechanism for replenishment.

12. In a loom having the shuttle-housing and picker mechanisms thereof and the slay of the loom carried on a swing rail, the combination of a revolvable multiple-compartment shuttle-box, each of the compartments of which constitutes a shuttle-box for housing an individual shuttle, means whereby the multiple-box may be revolved to bring each of the shuttle-housing compartments thereof opposite the picker for picking the shuttle thereof and be displaced therefrom when the shuttle is spent, and for a spent shuttle in a compartment of the multiple-box which is not opposite the picker to be presented to a purn-changing mechanism, a purn-changing mechanism including a stationary purn magazine mounted towards the front of the loom, a purn-transfer member, means whereby the initiation of the purn-change is made dependent upon the

previous rotation of the said multiple-box to displace a spent shuttle from opposite the picker and to bring a spent shuttle opposite the purn-changing mechanism, and means dependent for its operation upon a beating-up movement of the slay of the loom for only thereafter operating the said purn-transfer member to effect the transfer of a purn from the said magazine into the spent shuttle of that compartment of the multiple-box which has been brought into cooperative relationship with the said purn-changing mechanism.

13. In a loom having the shuttle-housing and picker mechanisms thereof and the slay carried on a swing rail, the combination of a revolvable multiple-compartment shuttle-box, each of the compartments of which constitutes a shuttle-box for housing an individual shuttle, means whereby the multiple-box may be revolved to bring each of the shuttle-housing compartments thereof in turn opposite the picker for picking the shuttle thereof and in turn in front of a purn-changing mechanism to replenish the spent shuttle with a fresh purn, a purn-changing mechanism including a stationary purn magazine mounted towards the front of the loom and a hammer-type purn-transfer member, and means whereby said purn-transfer member may be caused to operate at a beating up movement of the loom slay towards the front of the loom to effect the transfer of a purn from the said purn magazine into the shuttle of that compartment of the multiple-box which has been previously brought into cooperative relationship with the said purn-changing mechanism.

14. In a loom, the combination claimed in claim 13 wherein the multiple-compartment shuttle-box is mounted to partake of the same movement as the slay of the loom and the hammer-type purn-transfer member is operable, for a purn transfer, to strike a fresh purn out of the said magazine and into the shuttle of that compartment of the said multiple-box which has been brought into cooperative relation therewith as the said box moves towards the stationary magazine as the slay beats up, the spent purn being simultaneously forced out of the shuttle by the pressing home of the fresh purn into position, and wherein the construction of each compartment of the multiple-box is such as to allow the spent purn to fall away from the center of the compartment as the fresh purn is pressed into position.

15. In a loom having the shuttle-housing and picker mechanisms thereof and the slay of the loom carried on a swing rail, the combination of a revolvable multiple-compartment shuttle - box mounted to partake of the movement of the slay of the loom and each of the compartments of which constitutes a shuttle-box adapted to house an individual shuttle, means whereby a movement of partial rotation may be imparted to the said multiple-box to displace an individual shuttle-housing compartment thereof from opposite the picker of the loom and simultaneously to bring another shuttle-housing compartment thereof opposite the said picker and yet another shuttle-housing compartment thereof containing a spent shuttle opposite the magazine of a purn-changing mechanism, a purn-changing mechanism including a magazine for full weft purns which is non-movable with the slay of the loom, and a hammer-type purn-transfer member fulcrumed on the swing rail of the loom and adapted to be operated to strike a fresh purn from the said magazine into a spent shuttle in that compartment of the said

multiple-box which has been brought opposite the said magazine and simultaneously to force out the spent pirn from the said shuttle as the fresh pirn is pressed into position, whereby the said spent shuttle may be replenished with a fresh pirn without leaving its compartment of the multiple-box.

16. In a loom having the shuttle-housing and picker mechanisms thereof and the slay of the loom carried on a swing rail and weft-feeler motion for indicating the failure of the weft-thread, the combination of a revolvable multiple-compartment shuttle-box, each of the compartments of which constitutes the shuttle-box for housing an individual shuttle, the said multiple-compartment box being oscillatable with the slay of the loom, a pirn-changing mechanism including a stationary pirn magazine mounted towards the front of the loom and a hammer-type pirn-transfer member fulcrumed around the swing rail of the loom, and means operable under the control of the said weft-feeler motion for imparting a movement of partial rotation to the said multiple-compartment box upon the weft-thread failing, whereby to displace from opposite the picker that compartment of the multiple-box which contains the shuttle which has been spent and to bring opposite the said picker a compartment containing a shuttle which has been replenished with a fresh pirn by the said pirn-changing mechanism, the said means including a driving sprocket wheel mounted to partake of the movement of the slay of the loom, a chain drive from such sprocket wheel to the revolvable multiple-compartment box, and means controlled by the said weft-feeler motion for effecting a partial rotation of the said driving sprocket wheel upon the weft-thread failing.

17. In a loom having the shuttle-housing and picker mechanisms thereof and the slay of the loom carried on a swing rail and a weft-feeler motion for indicating the failure of the weft-thread, the provision of automatically operating weft-replenishing means comprising the combination of a revolvable multiple-compartment shuttle-box, mounted to partake of the movement of the slay of the loom and each of the compartments of which constitutes a shuttle-box adapted to house an individual shuttle, the said multiple-compartment box having at least three shuttle-housing compartments, a pirn-changing mechanism including a stationary pirn magazine mounted towards the front of the loom and a hammer-type pirn-transfer member fulcrumed around the swing rail of the loom, means operable under the control of the said weft-feeler motion for imparting a movement of partial rotation to the said multiple-compartment box upon the weft-thread failing, whereby to displace from opposite the picker that compartment of the multiple-box which contains the shuttle which has been spent

5 and simultaneously to bring opposite the said picker a compartment containing a shuttle which has been replenished with a fresh pirn by the said pirn-changing mechanism, and to bring opposite the said pirn-changing mechanism yet a further compartment of the box containing a spent shuttle ready to be replenished with a fresh pirn, said partial rotation of the multiple-compartment box taking place upon the weft-thread failing at a beating-up movement of the slay towards the front of the loom, and means operable at the next pick of the loom, also during the beating-up movement of the slay towards the front of the loom, to operate the said pirn-transfer hammer to strike a fresh pirn from the said magazine into the spent shuttle of that compartment of the multiple-box which has been brought opposite the said magazine and simultaneously to force out from the said compartment the spent shuttle.

18. In a loom having the shuttle-housing and picker-mechanisms thereof and the slay of the loom carried on a swing rail, the combination of a revolvable multiple-compartment shuttle-box mounted for movement with the slay on the said swing rail and having at least three compartments, each of which constitutes a shuttle-box for housing an individual shuttle, means whereby the said multiple-box may be revolved to bring each of the shuttle-housing compartments thereof in turn opposite the said picker for picking the shuttle thereof and in turn in front of a pirn-changing mechanism to replenish the spent shuttle with a fresh pirn, and a pirn-changing mechanism including a stationary pirn magazine and a pirn-transfer member fulcrumed on the swing rail of the loom, the arrangement being such that the replenishment of a spent shuttle when presented to the pirn-changing mechanism is effected, as the said slay and multiple-box move in a determined 20 direction around the said swing rail, by a counter-movement of the said pirn-transfer member in the opposite direction around the said swing rail, whereby both the fresh pirn and the spent shuttle move simultaneously towards one another on the same arc of a circle during the pirn-transfer.

19. In a loom, an oscillating slay, a revolvable shuttle-box on the slay, a stationary magazine containing full weft pirns in front of said box, and a hammer-type pirn changer including a hammer member fulcrumed coaxially with the oscillating slay and operable to press a full weft pirn from the magazine into a shuttle in the box containing an empty pirn and at the same time forcing the empty pirn out of the shuttle.

20. A loom as claimed in claim 18 characterized by a sprocket wheel and chain drive for the revolvable box, and catch for operating said sprocket wheel.
